US00D903990S

(12) **United States Design Patent** (10) Patent No.: **US D903,990 S**
(45) Date of Patent: **** Dec. 8, 2020**

(54) **FOOTWEAR COMPONENT**

(71) Applicant: **Lisias Ransan**, Boca Raton, FL (US)
(72) Inventor: **Lisias Ransan**, Boca Raton, FL (US)
(**) Term: **15 Years**
(21) Appl. No.: **29/677,396**
(22) Filed: **Jan. 19, 2019**

Related U.S. Application Data

(63) Continuation-in-part of application No. 29/668,677, filed on Nov. 1, 2016.

(57) **CLAIM**

The ornamental design for a footwear component, as shown and described.

DESCRIPTION

FIG. 1 is a front perspective view of my ornamental design for a footwear component;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a top plan view thereof; and,

FIG. 9 is a bottom perspective view thereof.

The broken lines depict portions of the footwear component that form no part of the claimed design.

1 Claim, 9 Drawing Sheets
